THEODORE WALLIS, ALFRED B. MATTOON, AND CHAUNCEY E. TUTLER,
OF AUBURN, NEW YORK.

Letters Patent No. 63,122, dated March 19, 1867.

IMPROVEMENT IN ATTACHING THILLES TO WAGONS.

The Schedule referred to in these Letters Patent and making part of the same.

TO ALL WHOM IT MAY CONCERN:

Be it known that we, THEODORE WALLIS, ALFRED B. MATTOON, and CHAUNCEY E. TUTLER, of Auburn, in the county of Cayuga, and State of New York, have invented certain new and useful improvements in Shackles for Attaching Thills to Wagons; and we do hereby declare that the following is a clear, full, and exact description of the same, reference being had to the annexed drawings, and the letters of reference marked thereon, as constituting a part of this specification, in which—

Figure 1 is a perspective.

Figure 2 represents the manner of constructing the lower end of the thill.

Figure 3 is a section of the shackle and thill attached.

The nature of our invention consists in providing a chamber in the head of the shackle, in which the lower end of the thill is placed, and secured by means of a slide, in the manner hereinafter fully set forth.

A represents the shackle, in the head of which is a chamber, said chamber being constructed in the manner represented in figs. 1 and 2. B is the lower end of the thill, which is provided with ears *a a*, and is designed to be placed in the chamber of shackle A. It should be observed that we make the ears *a a* rounding in order that the thill may work in the chamber as a hinge. C represents a slide, which should fit snugly into the chamber, though not too tight. The form of this slide is fully shown in fig. 3. d is a bolt, which passes through the shackle and also through the slide, in order that when said slide is properly placed it may be firmly secured. e is a nut, by means of which the bolt *d* is securely held. Thus it will be seen that when the lower end of the thill is properly adjusted in the chamber of shackle A, and the slide C is placed over the ears *a a* and secured by means of bolt *d* and nut *e*, a most simple and effective attachment is formed.

Having thus described our invention, what we claim is—

Shackle A, when provided with a receptacle, as described, in combination with slide C, as constructed, and both being employed in the manner and for the purpose set forth.

In testimony that we claim the foregoing as our own we hereby affix our signatures in the presence of two witnesses.

THEODORE WALLIS,
ALFRED B. MATTOON,
C. E. TUTLER.
